UNITED STATES PATENT OFFICE.

CHARLES W. KIRSCH, OF STURGIS, MICHIGAN, ASSIGNOR TO KIRSCH MANUFACTURING COMPANY, OF STURGIS, MICHIGAN, A CORPORATION OF MICHIGAN.

COMPOSITE DRAPERY FIXTURE.

Application filed October 13, 1926. Serial No. 141,257.

This invention relates to fixtures employed for window and other draping, and has for its object to provide a device of this character which consists of a main element, 5 such as an ordinary curtain-rod of the V-shaped type, and auxiliary adjustable and detachable parts for mounting either an additional curtain or drapery rod or rods, or a shade roller or both on the main element, and 10 for adapting the latter or an auxiliary rod carried thereby, to receive draperies of the pull-string type as distinguished from the ordinary type.

Modern window draping includes, in many 15 instances, three sets of drapes for some windows, two sets for others and one set for still others. One or more window-shades are also commonly used in conjunction with the drapes and, where more than one window-shade is used, it is frequently necessary to 20 mount the second shade roller outwardly of the window-casing. In draping glass doors, window-sashes, etc., it is desirable that the window-shade, if employed, shall constitute 25 a part of a single drapery fixture and it is the purpose and intent of this invention to provide attachments for a conventional type of curtain or drapery fixture to readily adapt the same to practically every drapery scheme, 30 with or without the addition of a window-shade.

Such a composite or combination fixture is not only advantageous from the standpoint of low cost, but also from the standpoint of compactness, ease of attachment and neat appearance, but from the point of view of the dealer, it possesses the great advantage of being enabled to meet the demands of the consumer from a comparatively small stock requiring only a limited capital investment.

The embodiment of the invention shown in the accompanying drawings includes the now most popular flat type of hollow curtain or drapery rod, it being quite obvious that the 45 several composite elements of the whole structure may be adapted for other types and shapes of rods without the exercise of invention.

The particular type of rod preferred to be 50 employed in connection with the several attachments illustrated, is that which is disclosed in Letters Patent No. 1,250,190, granted to me Dec. 18, 1917, having a single piece or integral middle or rod element. The 55 brackets employed are preferably of the type

disclosed by Letters Patent No. 1,488,256, granted to me on March 25, 1924, it being understood, of course, that other types of rods may be substituted without departing from the invention as defined in the appended 60 claims.

In the accompanying drawings illustrating the invention,—

Fig. 1 is a plan view of a fixture constructed in accordance with the invention. 65

Fig. 2 is a sectional view of the same on the line 2—2 of Fig. 1.

Fig. 3 is a perspective view of the bracket constituting a main attachment to the curtain rod constituting the principal or master fixture. 70

Figs. 4 and 5 are perspective views of auxiliary shade-roller supporting attachments adapted to be mounted in the main attachments illustrated in Fig. 3. 75

Fig. 6 is a perspective view of the fixture of Fig. 1 showing still other attachments mounted thereon.

Fig. 7 is a fragmentary view in elevation of the inner face of the rod or master fixture, 80 showing sheave blocks attached thereto.

Fig. 8 is a detail section on the line 8—8 of Fig. 7.

Fig. 9 is a plan section on the line 9—9 of Fig. 7. 85

Figs. 10 and 11 are perspective views of the sheave blocks detached from the master fixture.

While the present invention relates to a composite fixture equipped with detachable parts, it will be understood, of course, that the said detachable parts may be permanently associated with the master fixture in any well-known manner if desired, without the exercise of invention. Also that the attachments per se are useless without a master fixture and are, therefore, a part of the latter just as fully and entirely as if permanently secured thereto.

The master fixture or drapery rod per se is, as previously stated, preferably of the particular type illustrated and described in Letters Patent No. 1,250,190, which consists of a single straight piece 1 of hollow rod which may be conveniently defined as substantially of C-shaped section. This is now a conventional shape. On the ends of this rod 1 there are detachably telescopically mounted two bracket members 2 of L-shape, the outer end portions of whose arms are of the 110

same cross-sectional shape as the rod 1 and sufficiently large to receive and snugly fit the ends of the latter. The arms of each of the bracket elements 2 are of respectively different lengths so as to permit them to be interchangeably mounted on the rod 1 for varying the spacing of the latter from the window casing. Both arms of each bracket element 2 are provided with means for engaging the free arm with the bracket elements 3 on the window casing. The latter and the engaging means aforesaid may be of any suitable type other than that shown, the latter being preferred.

15 The flanges bordering the slots 4 in the rod 1 and the arms of the bracket elements 2 constitute very convenient means for mounting attachments on said several parts in such manner as to not obstruct the outer 20 surfaces of the front face and upper edges of the rod and to render said attachments substantially invisible from points within the room.

The rod 1 and bracket-elements 2 constitute what I shall hereinafter term the drapery rod. The latter may be used without attachments for ordinary curtains; with slides 5 for supporting portières or drapes to be parted when desired; and with sheave-blocks 6 and 7 for use in connection with the slides 5 and cords for manipulating the latter. The slides 5 shown are of the type described and claimed in Letters Patent No. 1,494,428, granted to me on May 20, 1924. 35 The sheave-blocks 6 and 7 are somewhat similar to those shown and described in Letters Patent No. 1,494,429, granted to me on May 20, 1924, in so far as they are somewhat similarly clamped in place.

40 It will be noted by reference to Figs. 8 to 10, that the sheave-blocks 6 and 7 consist of U-shaped sheet metal members, the arms of which are parallel. Between the latter there is mounted at least one sheave 9 having a central opening corresponding in diameter with a perforation in one of said arms and of larger diameter than the opposite perforation in the other arm. A set-screw having a long cylindrical head 10 and a threaded 45 shank 11, corresponding in diameter respectively with said several perforations, is passed through said arms and the bore of the sheave 9, the latter being thus rotatably mounted on the head 10 of said set-screw. The 50 threaded shank 11 of the latter is engaged in the threaded opening in a nut or plate 12 which is disposed within the rod so that said flanges of the latter bordering the slot 4 will, by rotating the set-screw in one direction, 55 be clamped between one arm of the sheave-block and said nut or plate 12. The arm of the sheave-block in contact with said flanges is provided with projections 13 which are bent to partly embrace the curved outer 60 edge portions of the rod to hold said block

against pivotal movement relatively to the rod. By disposing the nut and the opposed arm of the sheave-block so as to engage the over-lapped flanges of the rod 1 and a bracket element 2, the last-mentioned elements 70 may be clamped together.

The above construction is decidedly advantageous, in that the set-screw performs the several functions of permitting easy assembly of the block, sheave and nut. And 75 the whole structure, namely, the rod 1, bracket elements 2 and sheave-block and sheave are maintained in properly assembled relation by the single set-screw.

Where, as in the sheave-block 6, an additional sheave 14 is provided, the latter is equipped with integral trunnions which are sprung into perforations in the arms of the sheave-block. Said sheave 14 is of smaller diameter than the sheave 9 so that cords 85 trained over the respective sheaves and engaged with the master-slides at the meeting top corners of drapes, will not be disposed to interfere with each other.

It is obviously necessary that the outer 90 edges of the drapes of the pull-string type shall be secured against moving away from the bracket-elements 2 as the meeting edges are pulled toward each other to close a gap. This may be accomplished by disposing a 95 slide 5^a behind each of the sheave-blocks and one or more thereof on each of the arms extending to the wall-brackets, unless the space available for that purpose is lacking, because of the presence of the rod and shade-roller 100 supports 15.

Each of the latter comprises a middle or bridge-plate 16 adapted to be disposed within the rod and which is equipped with end-flanges indicated by the numerals 15, said 105 flanges being narrower than the bridge-plate 16, being so rendered by the recesses 15^a therein to receive the flanges bordering the slot 4, and the exposed portions of said flanges extending considerably above and below the said narrower portions and being of considerable width. The said flanges are spaced apart a distance equal to that separating the front and rear faces of the rod 1 and are held in this spaced relation by a 110 spacing rivet 17 which constitutes a support for a second rod 1^a, or for the bottom portion of a shade-roller supporting device herein-after described. The said spacing rivet 17 is so disposed that a rod 1 supported at its 115 ends upon said rivets in opposed supporting devices 15 will have its upper and lower edges disposed flush with those of the first-mentioned rod 1 and equally far below and above the upper and lower edges of the arms of the 120 elements 2. A bowed flat spring 18 mounted on the bridge-plate 16 bears at its ends against the outer wall of the bracket-element for frictional engagement to resist free sliding movement of the member 15. The latter is 125 130

provided with two perforated, downwardly extending projections 19 for permitting the outer edges of drapes to be secured thereto.

The members 15 are also adapted to receive the window-shade roller fixtures 20 and 21, which differ from each other only with respect to the openings to receive the respective end-elements of the conventional shade-roller. Each of said fixtures 20 and 21 consists of a U-shaped metal plate, the middle portion or bottom of which is adapted to rest upon the rivet 17. The inner flanges 22 of said members are provided at the sides of their free ends with projections 23 which are adapted to be disposed between the edges of the flanges 15 and the opposed flanges of the bracket-elements 2 and to rest at their lower edges, upon the bottoms of recesses 15^a constituting the narrow portions of the flanges 15 which pass through the slot 4. The outer flanges 23^a of said members 21 and 22 are provided with openings to receive the end members of the conventional window-shade roller.

From the foregoing it will be readily apparent that the master-fixture, consisting of the rod 1, the bracket-elements 2 and the wall plates, may be built up at small cost to suit almost every drapery scheme, the sole limitation residing in the length of the arms of the bracket-elements 2 which attach to the wall plates. A decided commercial advantage incident to this invention resides in the fact that the needs of patrons can be readily supplied by dealers from comparatively small stocks, and the advantage from the consumer's standpoint lies in ease of mounting, low cost and range of adaptability to changing styles of draperies.

I claim as my invention:

1. A drapery fixture including a master rod provided at its ends with arms, the latter having longitudinal slots in their opposed faces, said slots bordered by flanges, auxiliary fixtures such as a curtain rod or window-shade roller fixtures associated with the master rod, and brackets each housed in part by said arms and engaged with the flanges bordering said slots for interchangeably engaging and supporting said auxiliary fixtures.

2. A curtain rod including a master rod having hollow arms each provided in the face opposing the other with a longitudinal slot, an auxiliary fixture disposed behind the

main portion of the rod, auxiliary fixture supporting devices adjustably mounted on said arms and each including a part disposed within and engaging an inner surface of the rod and a protruding portion, the latter including substantially parallel vertical flanges between which the end portions of the auxiliary fixture are confined and a transverse support upon which the end portions of the auxiliary fixture are supported, said flanges adapted to maintain the auxiliary fixture in predetermined position on said support.

3. A drapery supporting fixture including a master curtain rod having end-arms, and an auxiliary fixture, supporting devices for said auxiliary fixture mounted on said arms and including supporting elements and retaining flanges, the latter and said supporting elements relatively arranged and spaced to adapt the same to receive a rod corresponding in shape to and in cross-sectional dimensions with the main portion of the master rod at the same elevation as the latter, and removable window-shade roller fixtures for said supporting devices, each including a flange having openings to receive the end-elements of a conventional shade-roller, and interengaging means on said shade-roller fixtures and said supporting devices for retaining the former in place upon the latter, said shade-roller fixtures interchangeable with said auxiliary rod.

4. Auxiliary adjustable fixture supporting means for hollow curtain rods having a longitudinal slot, comprising a pair of opposed socket-elements open at the top for receiving the ends of a rod or shade-roller fixtures, a member rigid with said socket-element disposed within the rod, a spring on said member for bearing on an inner surface of the rod, and recesses in said member for receiving the edges of the flanges bordering the slot in the rod, said spring serving to maintain a wall of each recess in firm contact with one of said flanges.

5. Auxiliary fixture supporting means for curtain rods including socket members open at the top for interchangeably receiving the ends of a rod or window-shade roller fixtures, window-shade roller fixtures formed to fit said socket member, and interengaging formation on the latter and the former for maintaining the same in interengaged relation.

CHARLES W. KIRSCH.
